UNITED STATES PATENT OFFICE.

CLIFFORD N. JOHNSON, OF TOLEDO, OHIO, ASSIGNOR TO THE CONKLIN PEN MANUFACTURING COMPANY, OF TOLEDO, OHIO, A CORPORATION OF OHIO.

PENCIL.

1,368,262.

Specification of Letters Patent.

Patented Feb. 15, 1921.

Application filed October 29, 1919. Serial No. 334,109.

To all whom it may concern:

Be it known that I, CLIFFORD N. JOHNSON, a citizen of the United States, and a resident of Toledo, in the county of Lucas and State of Ohio, have invented a certain new and useful Pencil; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

15 This invention relates to pencils of the lead feeding type, and has for its object to provide certain improvements therein whereby to enhance the practicability and commercial value thereof.

20 The invention is fully described in the following specification, and while, in its broader aspect, it is capable of embodiment in numerous forms, a preferred embodiment thereof is illustrated in the accompanying drawings, in which,—

Figure 1 is an elevation of a pencil embodying the invention. Fig. 2 is an enlarged central longitudinal section thereof with parts in full. Fig. 3 is a cross-section 30 on the line 3—3 in Fig. 2. Fig. 4 is a plan view of the spider member disposed in the rear end of the pencil barrel. Fig. 5 is a perspective view of the ferrule member attached to the rear end of the spiral tube, 35 and Fig. 6 is a fragmentary side view, partially in central longitudinal section, of the lead receiving and feeding means.

Referring to the drawings, 1 designates the barrel of the pencil which barrel is tubular in cross-section in the present instance, and is fixed at its inner or forward end and has a collar or bushing 2 inserted within and rigidly secured to its inner or forward end with the outer end of the collar projecting a short distance therefrom. The 45 tapered tip member 3 of the pencil is rotatably mounted at its inner end on the projecting end of the collar or bushing 2 to permit a relative turning of the barrel and tip as is customary in pencils of this type. The lead feeding tube 4 is fixed at its forward or outer end to the contracted forward end of the tip 3 and projects rearwardly therefrom centrally through the tip 50 and collar 2, having a turning fit in the

latter, and terminates at its rear end adjacent to the rear end of the barrel 1.

A spiral tube 5, of the type customarily employed in pencils of this character, is disposed within the barrel 1 and is fixedly connected thereto for turning movements therewith through the medium of the collar 2, the spiral tube in the present instance being fixed at its forward end in an enlarged portion of the opening of the collar 2. The 60 spiral tube 5 encircles the lead feed tube 4 for free turning movements relative thereto and terminates at its rear end short of the rear end of the feed tube 4, as shown.

A tubular ferrule member 6 is fixed to and projects rearwardly from the rear end of the spiral tube 5, being of suitable size to fit over said tube, and has its rear end contracted and formed with a terminal nipple 7 into which a stem 8 fits and is rigidly secured by soldering, welding or any other suitable manner. The rear end of the feed tube 4 has a pair of cylindrical nuts 9 threaded on its rear end without the tube 5 and within the enlarged portion of the ferrule 6 to coöperate with the ferrule to rotatably center the feed tube therein and to coöperate with the adjacent end of the spiral tube 5 to prevent a withdrawal of the tube 4 from the tube 5. Two nuts 9 are employed so that one may be adjusted to have a turning fit against the end of the spiral tube 5 and the other is provided as a lock nut to secure the adjusting nut in adjusted position. It is preferable to project the stem 80 8 a sufficient distance into the ferrule to abut against the end of the tube 4 to oppose a rearward end thrust thereof.

A tube 10 of longitudinally corrugated form is loosely inserted in the annular space 95 between the barrel 1 and spiral tube 5 and coöperates with the barrel to form a magazine for holding a plurality of leads 11, one of which may be inserted in each of the pockets formed by the external recesses or corrugations of the tube. The tube 10 is retained within the barrel by a collar 12 of spider form, which is threaded on the stem 8 and is adapted to fit into the rear end of the barrel 1 in end abutment with the magazine tube to prevent play or rattling thereof within the barrel. The spaces between the arms of the spider 12 are intended to register with the spaces or pockets in the magazine tube in which the leads are disposed, 110

thus enabling the leads to be readily inserted into or moved from the magazine without removing the collar. The enlarged portion of the ferrule 6 is provided with a plurality 5 of longitudinal slots 13 positioned to receive the inwardly projecting edge portions of the magazine tube so that the magazine and ferrule are prevented from relative turning movements. This also enables a 10 magazine tube, having corrugations of greater depth than the space between the ferrule 6 and barrel 1, to be employed.

It is evident that the ferrule 6 and stem 8 form a journal for the rear end of the spiral 15 tube 5 and a bearing for the inner tube 4, and that the member 12 centers said journal relative to the barrel 1 or coöperates with the ferrule and stem to form a means for centering the tubes 4 and 5 at their rear ends 20 within the barrel and carrying them for relative rotary movements.

A cap 14 is screwed onto the outer end of the stem 8 without the spider 12 and against the rear end of the barrel 1, thus serving to 25 close the openings in the spider and access to the leads in the magazine.

The lead feeding and retracting means employed is similar to that used in pencils of this type and includes a plunger member 30 15, which is mounted for reciprocatory movements in the feed tube 4 and is located at its forward end to permit the rear end of a lead to be fitted therein. A stud 16 projects transversely from the plunger 15 35 through a longitudinal slot 17 in a side of the feed tube 4 and thence into the spiral slot 18 formed in the tube 5. It is thus evident that upon a relative turning of the barrel 1 and tip 3 the tubes 4 and 5 will have 40 corresponding relative turning movements imparted thereto thereby causing the spiral tube to impart either a lead feeding or retracting movement to the plunger 15 depending on the direction of relative turning of the tubes. The barrel 1, tip 3 and tubes 4 and 5 are retained in assembled relation by 45 reason of the rear end of the tube 4 being provided with a shoulder, which, in the present instance, is formed by the nuts 9, that is 50 rotatably mounted and centered in the ferrule 6 and in end abutment with the rear end of the spiral tube 5.

The ferrule 6 is not soldered or otherwise 55 fixedly secured to the rear end of the tube 5 until the proper adjustment of the nuts 9 has been effected relative to the tubes 4 and 5 to take up any end play between the two and at the same time permitting free relative turning movement thereof. After such 60 adjustment has been accomplished the ferrule 6 is inserted over the rear ends of the tubes and fixedly secured by soldering or in any other suitable manner to the rear end of the tube 5.

65 I wish it understood that my invention is

not limited to any specific construction, arrangement or form of the parts, as it is capable of numerous modifications and changes without departing from the spirit of the claims.

Having thus described my invention, what I claim as new, and desire to secure by Letters Patent, is,—

1. In a pencil of the class described, a barrel and a tip mounted for relative rotary 75 movements, a spiral tube disposed within the barrel and fixed thereto, a ferrule fixed to the rear end of said tube, means centering the ferrule in the barrel with a part thereof removably engaged to the latter, a corrugated magazine tube disposed within the barrel in encircling relation to the spiral tube and in interengagement with the ferrule to prevent a relative turning of the ferrule and magazine tube, and a lead feed 80 tube fixedly projected from the tip through the spiral tube and having its rear end journaled in the ferrule and shouldered against the rear end of the spiral tube.

2. In a pencil of the class described, a barrel and tip mounted for relative rotary movements, a spiral tube disposed within the barrel and fixed thereto, a ferrule fitting over and fixed to the rear end of said tube and having its outer end reduced and its 95 large portion longitudinally recessed, a corrugated magazine tube disposed between the barrel and spiral tube and having the inner portions of its corrugations fitting into the recesses of the ferrule to prevent a relative 100 turning of the ferrule and magazine tube, means without the tube for centering the ferrule in the rear end of the barrel, said means having openings in register with the lead receiving pockets of the magazine, 105 means for closing said openings, and a lead feed tube fixed to and projecting rearwardly from the tip through the spiral tube and having its rear end journaled in the ferrule and shouldered against the rear end of the 110 spiral tube.

3. A pencil of the class described, having relatively rotatable barrel and tip members, lead-actuating mechanism, including a spirally slotted tube fixed to the barrel and 115 an inner slotted tube fixed to the tip, a journal for the rear end of the spirally slotted tube and coöperating with said tube to form a bearing for the rear end of the inner slotted tube, means centering said journal 120 within the rear end of the barrel, and a magazine for extra leads disposed between the spirally slotted tube and barrel.

4. A pencil of the class described, having relatively rotatable barrel and tip members, lead-actuating mechanism, including an inner longitudinally slotted tube fixed to the tip and an outer spirally slotted tube fixed to the barrel, a magazine for extra leads surrounding the outer tube, and means center- 125 130

ing the rear ends of said tubes within the barrel and carrying them for relative rotary movements and having a part releasably engaging the magazine to prevent a turning 5 thereof relative to said means.

5. A pencil of the class described, having relatively rotatable barrel and tip members, lead-actuating mechanism, including a longitudinally slotted inner tube fixed to the tip 10 and an outer spirally slotted tube fixed to the barrel, a corrugated magazine for extra leads surrounding the outer tube within the barrel, a journal on the rear end of the outer tube coöoperating with the tube end to form a 15 bearing for the rear end of the inner tube and releasably engaging the magazine to prevent a relative turning thereof, means for centering the journal within the rear end of the barrel and having openings in communication with the lead holding recesses of the 20 magazine.

6. A pencil of the class described, having relatively rotatable barrel and tip members, lead-actuating mechanism disposed 25 therein and including an outer spirally slotted tube fixed to the barrel and an inner longitudinally slotted tube fixed to

the tip and having an end thrust bearing against the rear end of the outer tube, a magazine for extra leads surrounding the outer 30 tube, and means having a part releasable with respect to the barrel, said means centering the rear end of the outer tube therein and preventing a turning of the magazine relative to the outer tube.

7. A pencil of the class described, having relatively rotatable barrel and tip members, lead-actuating mechanism disposed therein and including an outer spirally slotted tube fixed at its forward end to the barrel and an 40 inner longitudinally slotted tube fixed at its forward end to the tip, an outer tube having a journal at its rear end, a magazine having extra leads surrounding the outer tube and engaged to said journal to prevent relative 45 rotation thereof, and a collar threaded on the journal and engaging the rear end of the barrel to center the tubes and the journal therein, said collar having openings in register with the lead receiving pockets of the 50 magazine.

In testimony whereof I have hereunto signed my name to this specification.

CLIFFORD N. JOHNSON.
